UNITED STATES PATENT OFFICE.

WILLIAM H. RYAN, OF NATICK, AND MYRON W. BENT, OF WAYLAND, MASSACHUSETTS; SAID RYAN ASSIGNOR TO SAID BENT.

MACHINE FOR APPLYING SOLE-LININGS.

SPECIFICATION forming part of Letters Patent No. 432,839, dated July 22, 1890.

Application filed November 16, 1889. Serial No. 330,571. (No model.)

To all whom it may concern:

Be it known that we, WILLIAM H. RYAN, of Natick, and MYRON W. BENT, of Wayland, both in the county of Middlesex and State of 5 Massachusetts, have invented certain new and useful Improvements in Machines for Applying Sole-Linings or False Inner Soles to Boots or Shoes, of which the following is a specification.

10 This invention relates to means for applying a sole-lining or false inner sole to the interior of a boot or shoe for the purpose of covering the inner sole proper and the stitches or other fastenings that secure the upper to 15 the outer and inner soles. A sole-lining or false inner sole is usually secured to the inner sole proper by paste or cement, and heretofore said lining has been inserted into the boot or shoe by hand and spread out by a 20 stick manipulated by the hand of the operator, the operation being necessarily slow and liable to form wrinkles in the lining.

Our invention has for its object to provide a machine adapted to engage and hold the 25 lining or false inner sole in shape while it is being inserted into the boot or shoe, to press it to place upon the inner sole proper, and to release it after it is pressed to place, so that upon the removal of the boot or shoe the lining or false inner sole will not be held by 30 said machine.

To these ends our invention consists in the improvements which we will now proceed to describe and claim.

35 In the accompanying drawings, forming a part of this specification, Figure 1 represents a side elevation of our improved machine. Fig. 2 represents a sectional view of the principal portions of the same on a larger scale. 40 Fig. 3 represents a top view of the machine. Fig. 4 represents a perspective view of the plate that supports the lining or false inner sole. Fig. 5 represents a side view of the machine, showing the lining or false inner sole 45 released and ready for removal with the boot or shoe.

The same letters of reference indicate the same parts in all of the figures.

In the drawings, *a* represents a supporting- 50 standard adapted to be attached to a floor or

other support. Secured to the top of said standard is a tubular holder *b*.

c represents a sole-shaped plate, which is provided at the heel end with a shank *c'*, adapted to enter the holder *b*, said shank 55 having a shoulder *e*, which bears upon the upper end of the holder *b*, so that the plate is firmly supported by the holder.

f represents an arm, which is supported by a spring *g* within the holder *b*, said spring 60 bearing on a fixed support *i* at its lower end and against a head or enlargement *j* on a shank *k*, which is formed on the arm *f*, so that the spring normally holds the arm up against the under side of the plate *c*, and causes upwardly-projecting pins *m m*, inserted in said arm, to project through apertures *n n* in the plate.

o represents a treadle, pivoted at the lower portion of the standard *a* and connected by 70 rods *p p'* with the arm *f*, the arrangement being such that the depression of the treadle *o* causes the depression of the arm *f* and the pins, as shown in Fig. 5.

The operation is as follows: The lining or 75 false inner sole *s* is placed upon the plate *c* when the pins *m* are in the position shown in Figs. 1 and 2, the points of the pins being held above the upper surface of the plate, so that they will penetrate the lining or false 80 inner sole, and thus hold the latter in place on the plate *c*. The upper surface of the lining *s* is then coated with cement, after which the boot or shoe is drawn upon the plate *c* and pressed down sufficiently to cause contact of 85 the inner sole with the cement-coated lining. The arm *f* is then depressed and withdraws the pins *m* from the lining *s*, leaving the latter free to be removed with the boot or shoe to which it is cemented. It will be seen that 90 by this contrivance the lining is quickly applied, and all liability of wrinkling the lining during its application is obviated.

We claim—

1. In a machine for applying sole-linings 95 or false inner soles to boots or shoes, the combination of the fixed supporting-plate *c*, having apertures through it, the movable arm *i*, located under said plate and having upwardly-projecting pins arranged to project 100

through said apertures and enter a lining or sole on the plate *c*, a spring arranged to force the arm upwardly and cause its pins to project above the plate *c* and enter the lining or sole, and means for depressing said arm and thereby withdrawing the pins and releasing the sole or lining, as set forth.

2. In a machine for applying sole-linings or false inner soles, the combination of the rigidly-supported plate *c*, having apertures *n*, and the hollow shank *c'*, the tubular holder *b*, adapted to receive said shank and rigidly support the plate *c*, the arm *f*, adapted to move in the shank *b*, and provided with upwardly-projecting pins coinciding with the apertures in the plate *c*, the spring *g* within

the tubular holder *b*, whereby said arm is pressed upwardly against the plate *c*, the pivoted treadle *o*, and connections between said treadle and the arm *f*, whereby the arm and pins may be depressed to withdraw the pins from a sole on the upper surface of the plate *c*, as set forth. 20

In testimony whereof we have signed our names to this specification, in the presence of 25 two subscribing witnesses, this 23d day of October, A. D. 1889.

WM. H. RYAN.
MYRON W. BENT.
